DESIGN FOR A JEWELRY ELEMENT FOR BRACELETS OR SIMILAR ARTICLES

Louis Mazer, New York, N. Y.

Application March 13, 1939, Serial No. 83,537

Term of patent 3½ years

To all whom it may concern:

Be it known that I, Louis Mazer, a citizen of the United States and a resident of New York city, in the county of New York and State of New York, have invented a new, original, and ornamental Design for a Jewelry Element for Bracelets or Similar Articles, of which the following is a specification, reference being had to the accompanying drawing, forming part thereof, and in which

Fig. 1 is a plan view of a jewelry element showing my new design, and

Fig. 2 is a side elevation of the design.

I claim:

The ornamental design for a jewelry element for bracelets or similar articles, substantially as shown.

LOUIS MAZER.
